COMBINED BOSOM AND COLLAR AND
CUFF PRESSEdwin A. Mall, Norwood, Ohio, assignor to The
American Laundry Machinery Company, Nor-
wood, Cincinnati, Ohio, a corporation of Ohio

Application February 9, 1934, Serial No. 710,486

10 Claims. (Cl. 38—22)

This invention relates to a combined shirt bosom and collar and cuff pressing or ironing machine.

Separate machines have heretofore been provided for the pressing or ironing of these parts of men's shirts, that is to say, one machine for pressing bosoms and back yoke portions, and another machine for pressing collars or neckbands and cuffs. Many users of laundry equipment have a sufficient volume of work to justify the purchase of one machine but not sufficient to justify an investment in two machines. Such establishments, therefore, do the work by hand and are deprived of the benefits both as to labor saving and improved appearance which is the result of machine operations. One object of my invention is to provide, in one machine, combined equipment for machine finishing the bosoms and collars and cuffs of men's shirts, thus for the first time, to my knowledge, making commercially practicable the machine finishing of these parts in small establishments.

Another object of the invention is to arrange a machine of the class just described adaptable to the finishing of collar-attached or neckband style shirts with very little adjustment on the part of the operator.

A more specific object of the invention is to provide a buck adapted to press the bosoms of shirts in coaction with a chest having a recessed portion to accommodate the neckband of the shirt during the bosom pressing operation, and a second buck adapted to press collars and cuffs and arranged to move selectively into coaction with the same chest but arranged to coact with the unrecessed portion of the chest.

Other objects and advantages of my invention will appear from the accompanying specification together with the drawings in which like reference characters refer to similar parts in the various views.

In the drawings, Fig. 1 is an elevation of one type of pressing machine embodying my invention with the bosom buck in pressing engagement with the chest and the collar and cuff buck unit in loading position; Fig. 2 is a plan view of the pressing machine of Fig. 1, the upper portion of the frame and the chest being broken away to show the arrangement of the bucks; Fig. 3 is a plan view of the left portion of Fig. 2 showing one of the pressing elements thereof in reversed position to accommodate a different style of shirt; Fig. 4 is a section along the line 4—4 of Fig. 3 omitting the garment; while Fig 5 is a section on the line 5—5 of Fig. 3 omitting

the garment and showing the upper surface of the buck elements in full elevation.

My invention is applicable to any press where a plurality of pressing beds are movable into cooperation with a single chest and the special arrangement of the collar and cuff pressing elements is applicable to any type of press. I have chosen to illustrate my improvements as applied to a press of the type illustrated, described and claimed in the Patent No. 1,997,219, 10 granted April 9, 1935, to Oscar W. Johnson, which shows power means for rotating the buck units alternately into coacting position with a single chest. However, it will be understood by those skilled in the art that my improvements 15 are equally applicable to a press of the type shown in Patent No. 1,115,187, granted October 27, 1914 to A. T. Hagen and D. M. Cooper, where the buck-carrying frame is movable by hand.

The press illustrated comprises a fixed frame portion 10 supporting a chest 11, which may be heated in any well known manner, and a rotatable frame portion 12 carrying a bosom buck 13 and a combined collar and cuff buck unit 14. 25 The bucks 13 and 14 are movable alternatively into position to coact with the chest 11. The bucks are arranged for vertical movement relative to the rotatable frame by means of pressure pins 15 and 16 depending from the bucks 30 through suitable bores in the frame in position to register with and be raised by the rod 17 of a piston 18 enclosed in a suitable cylinder 19 in the stationary frame portion 10. As stated above, the frame 12 may be rotated by hand 35 although the mechanism shown illustrates power means for rotating the bucks. This power means forms no part of this invention, reference being had to the above mentioned Johnson patent for further description thereof if desired. Suitable means is provided, indicated generally at 20, for stopping a buck in registering position beneath the chest whereupon fluid under pressure is admitted to cylinder 19 beneath the piston 18 by a valve arrangement 45 indicated generally at 21. This raises the registering buck into pressing or ironing engagement with the chest 11. Upon completion of the pressing operation the fluid pressure control valves are reversed to exhaust the cylinder, the 50 parts move downwardly out of ironing engagement by their own weight, and the frame is rotated 180° to reverse the position of the bucks. All this is old in the art and further description is thought unnecessary.

The bosom buck 13 is substantially of standard design, that is to say, it is substantially rectangular in form as seen in Fig. 2, and provided at one end with back yoke holding members 22 and a neckband former 23. The chest 11 has a recessed portion 24 adapted to accommodate the neckband former, the rest of the chest forming an unrecessed portion adapted to press the bosom when cooperating with the bosom buck and adapted to press a collar or neckband and cuffs when the second buck unit is moved into registering position.

The buck unit 14 comprises separate pressing elements or surfaces adapted to lie within the area of the unrecessed portion of the chest and having a curvature or contour complementary to the curvature of the chest so as to coact therewith in an ironing operation. In the instant embodiment, the buck unit 14 comprises a pressing element 25 having a surface substantially rectangular in plan and having a sufficient area to accommodate a pair of cuffs as shown in Figs. 2 and 3. A second pressing element 26 has a surface substantially reniform in plan with a downwardly extending boss 42 adapted to fit into a corresponding recess 43 in a pedestal 28 to guide element 26 for rotation to either of two positions. A pin 27 located centrally thereof secures the buck element to the pedestal. One position is illustrated in Fig. 2 with the concave edge toward element 25. This arrangement is used for collar-attached shirts. Fig. 3 shows buck element 26 in reversed position with its convex edge toward the cuff pressing element, this position being adapted to iron the neckband type of shirt. It is thus possible to simultaneously iron the cuffs of a shirt on pressing element 25 and the collar or neckband of the shirt on element 26, the latter element being turned into whichever of its two positions is necessary to iron the style of shirt being processed.

Clamps are provided for holding the neckband in position, these being clearly shown in Figs. 3 and 4 as comprising clamping portions 29 having downwardly extending arm portions 30 substantially normal to the clamping portions and carried in guides 31 extending longitudinally of the neckband. The clamps are maintained in clamping position by tension springs 32 extending from the lower ends of the arm portions to the pedestal and attached preferably by pivotal connections to brackets 33 on the buck pedestal. Handles 34 are provided to manipulate the clamps. The clamps are easily moved to various positions longitudinally of the buck element or neckband by moving them arcuately about the spring pivots.

The two buck elements 25 and 26 are preferably supported on a common pedestal 28 which may be made hollow as shown in Figs. 4 and 5 and provided with an outlet conduit 44 for the removal of condensate from the buck elements. This removal is accomplished by way of passageway 35 leading from element 25 and passageways 36 in buck element 26, these latter passageways being equally spaced from pin 27 and adapted to register with coacting openings 37 in the buck pedestal in both positions of element 26. For maintaining element 26 in either of its two positions a spring pressed ball 38 may be provided in a recess in the pedestal with depressions 39 and 40 in the lower surface of element 26 on opposite sides of pin 27 and into which the ball 38 may enter when the element reaches its proper positions. The buck element 26 is easily

rotated against the pressure of the spring pressed ball by a pull on one end of the buck element. The pedestal 28 is guided in its vertical movement by a rod 28a engaging in a bore 41 in a bracket extension on the frame 12.

In the operation of this machine at the start of the day's work, the operator places a first garment in position on the collar and cuff buck unit, as shown in Figs. 2 or 3 depending on the type of shirt to be pressed. The frame 12 is then rotated 180° to position the garment beneath the chest and the ironing operation on the collar and cuffs is performed. The frame is then rotated 180° back to the loading position, the operator removes the first shirt of which the collar and cuffs have been pressed and places it on a hanger. She then places a second shirt on the collar and cuff buck unit and repeats the above operation. This brings the bosom buck into loading position and she takes the first shirt previously placed on a hanger and arranges it on the bosom buck in position to press the bosom thereof. The frame is again rotated whereupon the collar and cuff buck unit is again brought to loading position while an ironing operation takes place on the bosom buck. The second shirt is removed from the collar and cuff buck unit and a third shirt placed thereon and thereafter the frame is rotated 180° and the completely ironed first shirt is removed from the bosom buck. This process is repeated throughout the day's work, each shirt having the collar and cuffs ironed first, then being removed to a hanger and placed on the bosom buck at the next operation.

The owner of a small establishment is enabled by the use of my improved machine to obtain machine finishing of the bosoms and collars and cuffs of men's shirts with a minimum investment. When a growing volume of business warrants it, a second machine may be purchased like the first, or each machine may be provided with two bucks just alike, or the first machine may be transformed into a bosom pressing machine of the type disclosed in the above-mentioned Johnson patent and a collar and cuff machine of a different type may be grouped therewith.

What I claim is:

1. In a pressing machine, a chest, a buck having two spaced pressing elements adapted to coact with said chest, one of said elements having different shaped edges, and means enabling the reversing of the position of said one element to present either of its said edges toward the other element, whereby to accommodate articles having spaced portions to be ironed, one of which portions may vary as to shape.

2. A pressing member comprising two spaced pressing elements mounted on a common base member, one of said elements being substantially rectangular and adapted to accommodate two shirt cuffs thereupon, the other of said elements having opposed edges, one edge concave and the other edge convex for ironing shirt collars of different shape, and means enabling the reversing of the position of said last-named element to present its concave or convex side toward the first named element, whereby the collar and cuffs of shirts of different styles may be simultaneously ironed.

3. In a press of the class described having a pressing element adapted to accommodate work of various lengths mounted on a support, an L-shape clamp having a clamping portion adapted to engage the work against the pressing surface of said element, an arm portion extending sub-

- stantially normal to said clamping portion, means mounting said arm portion for movement to various positions along said pressing surface, said mounting means including means biasing 5 said clamping portion toward said pressing surface, and means for retaining said clamping portion over said pressing surface in various positions of said clamp.
4. In a press of the class described having a 10 pressing element adapted to accommodate work of various lengths mounted on a support, an L-shape clamp having a clamping portion adapted to engage the work against the pressing surface of said element, an arm portion extending 15 substantially normal to said clamping portion, a tension spring connected between the free end of said arm portion and said pressing element support for biasing said clamping portion toward said pressing surface, and means for retaining 20 said clamping portion over said pressing surface in various positions of said clamp.
5. In a pressing machine, an ironing chest 25 having a substantially horizontal pressing surface with a neckband recess therein, two buck members movable alternately into registration with said chest, one buck member comprising a bosom board always in a horizontal position and having a neckband former, the other buck member having two pressing surface parts always 30 horizontal, one part for a shirt collar, the other part for shirt cuffs, said other buck member being adapted as a unit to cooperate with the un- 35 recessed portion of said chest, and means for causing relative ironing approach between said chest and each buck member when in registration therewith.
6. A pressing machine as in claim 5, and in which said collar pressing part of said other buck member is provided with edges of different 40 conformation, and said shirt collar part is arranged to selectively move each of said edges into position next to said cuff pressing part, whereby shirts having varying collar styles may be 45 pressed on the one machine.
7. In a pressing machine, an ironing chest having a substantially horizontal pressing surface, two buck members movable alternately into registration with said chest, one buck member comprising a bosom board always in a horizontal 50 position and adapted to coact with said chest in a shirt body pressing operation, the other buck member having two pressing surface parts always horizontal, one part for a shirt collar, the 55 other part for shirt cuffs, said parts being arranged with a space between them adapted to receive the body of a shirt while the collar and cuffs thereof are being pressed, said other buck member being adapted as a unit to cooperate 60 with said chest, and means for causing relative ironing approach between said chest and each buck member when in registration therewith.
8. In a pressing machine, an ironing chest having a substantially horizontal pressing surface with a neckband recess therein, a frame 5 rotatable about a vertical axis, two buck members mounted on said frame and movable by frame rotation alternately into registration with said chest while exposing the non-registering member adjacent an operator, one buck 10 member comprising a bosom board always in a horizontal position and having a neckband former, the other buck member having two pressing surface parts always horizontal, one part for a shirt collar, the other part for shirt cuffs, said 15 parts being arranged with a space between them adapted to receive the body of a shirt while the collar and cuffs thereof are being pressed, said other buck member being adapted as a unit to cooperate with the un- 20 recessed portion of said chest, and means for causing relative ironing approach between said chest and each buck member when in registration therewith.
9. In a pressing machine, a frame, an ironing chest on said frame having a substantially horizontal pressing surface, a buck support mounted in said frame for rotation about a vertical axis, two buck members on said support and movable by support rotation to register one buck member 25 with said chest while exposing the other buck member adjacent an operator's position, one buck member comprising a shirt body pressing member, the other buck member having two pressing surface parts, one part for a shirt collar, the other part for shirt cuffs, said parts being 30 arranged with a space between them adapted to receive the body of a shirt while the collar and cuffs thereof are being pressed, said other buck member being adapted as a unit to cooperate 35 with said chest, means for causing relative ironing approach between said chest and each buck member when in registration therewith, and means mounting said other buck member 40 removably on said support whereby said other buck member may be replaced by a shirt body 45 pressing buck member.
10. In a pressing member having an element for pressing a cuff portion of a shirt of collar or neckband type, an element spaced from said cuff pressing element and having edges of different 50 shape, one edge being concave and adapted for pressing the collar of one type of shirt, another edge being convex and adapted for pressing the neckband of another type of shirt, and means whereby said last named element may be moved 55 to present either of said edges toward the cuff pressing element to permit simultaneous pressing of the collar or neckband and the cuff portion of a shirt.

EDWIN A. MALL. 60
